UNITED STATES PATENT OFFICE

2,443,981

GREASE GUN CHARGER

Frank F. Funk and Robert D. Funk, Ottawa, Ill.

Application March 19, 1945, Serial No. 583,414

3 Claims. (Cl. 226—125)

1

The present invention relates to a grease gun filler or charger.

To fill grease guns it has been the custom to remove the rear end cap of the gun barrel and also the piston, and to then feed in the grease into the barrel after which the piston was introduced and the cap screwed on the end of the barrel. That was a rather messy job, much of the grease was lost, air would be entrapped into the grease in the barrel and dirt would also become mixed with the grease.

Among the objects of the present invention is to produce a novel device that avoids such disadvantages and wherein the grease is fed directly into the forward end of the gun in front of the piston without any loss of grease and without any entry of air and dirt.

Another object of the invention is to provide a novel means for use with a commercial grease container and which has a diaphragmatic piston for acting under atmospheric pressure and throughout the extent of the grease mass in the container for efficient feed of the grease to the device for charging the grease gun, and being in sealing relation with the container to prevent loss of the grease and to prevent access of air and dirt into the grease.

Other objects, advantages, capabilities, features and the like are comprehended by the invention as will later appear and as are inherently possessed by the invention.

Referring to the drawings:

Fig. 1 is a view partly in elevation and partly in section of an embodiment of the invention;

Fig. 2 is a longitudinal sectional view of the device; and

Fig. 3 is a transverse fragmentary sectional view taken in a plane represented by line 3—3 in Fig. 2 of the drawings.

Referring more in detail to the drawings, the embodiment chosen to illustrate the invention is shown as comprising an outer hollow cylinder 1 in which telescopes and reciprocates an inner hollow cylinder 2 having a free open lower end 3 and a reducing coupling 4 at its upper end. To the lower end of the cylinder 1 is fixed a diaphragm 5 by way of a flanged collar 6 suitably secured to the lower end of the cylinder 1 and to the central portion 7 of the diaphragm 5, as shown. The perimetral portion of the diaphragm 5 has a shoulder or fillet 8 for holding an annular packing 9.

The lower end of the cylinder 1 has an end wall 10 abutting with the central portion 7 of the diaphragm 5, and both these parts 7 and 10

have a valve port or seat 11 for the seating thereon of a valve 12 normally under the stress of a spring 13 held compressed between the valve 12 and a spider 14 suitably secured within the cylinder 1 spacedly above the valve 12, as shown in Fig. 2. On the lower end portion of the cylinder 2 is carried a sealing ring 15. Within the upper end portion of the cylinder 2 is fixed a wall or disc 16 having a valve port or seat 17 for the seating thereon of a valve 18 normally under the stress of a spring 19 held compressed between the valve 18 and a spider 20 suitably fixed to and within the cap or coupling 4, as shown in Fig. 2. To the upper end of the cap 4 is connected a nipple 21 which may have a threaded upper portion 22.

This device is designed for use with a commercial type of grease container having a cylindrical body 23 provided with a bottom 24 and for containing grease 25. On the barrel or cylinder 1 may be slidably associated a cover 26 having a resilient rim 27 adapted to snap onto the upper rim 28 of the container 23 after the usual cover that comes with the container 23 has been removed. The diaphragm 5 fits closely within the container 23 over the whole area of the grease 25 and with the packing 9 in sealing engagement with the inner wall of the container 23 so that as the atmosphere forces down the diaphragm 5 upon the grease 25 the grease will remain level.

To the upper end of the nipple 21 is connected a grease gun 29 having a barrel 30, a nozzle 31, a stem 32, a tip 33, a piston 34 slidably in the barrel 30, a piston rod 35 passing through the rear cap 36 on the barrel 30, and a handle 37 on the exterior end of the piston rod 35.

Secured to a side portion of the nozzle chamber 31 is a stub or nipple 38 preferably having a suitable check valve 39 therein and rotatably connected with this nipple is a coupling nut 40 adapted for ready connection with and disconnection from the threaded portion 22 of the nipple 21.

In use, when the piston 34 of the gun has reached its inward position at the end of the greasing operation, see Fig. 1, the nipple 38 is connected to the nipple 21 by screwing the coupling nut 40 upon the threaded end 22, and then, using the gun 29 as a handle, the cylinder 2 is forced down in the cylinder 1, whereupon the grease in the cylinder 2 moves up by way of the valve 18, coupling 4, nipples 21 and 38 and into the chamber of the nozzle 31, to move the piston 34 rearwardly until the gun is filled with the grease. Then the gun is disconnected. The

check valve 39 automatically closes to prevent loss of grease from the nozzle 31.

When the cylinder 2 is pulled upwardly, the valve 18 closes and the atmospheric pressure acts down on the diaphragm 5 to force grease 25 from the container 23 by way of the valve 11-12 into the barrel 1, below and against the grease already in the cylinder 2. Because the diaphragm 5 is of comparatively much greater effective area than that of the cylinder 1 the downward thrust of the atmosphere upon the diaphragm 5 is much greater than the upward pull of the cylinder 2. Therefore, there is no necessity for holding the cylinder 1, as by the operator's hand, when the cylinder 2 is pulled up.

While the invention has been described in an illustrative way as applicable to the supplying or charging of grease to a grease gun, it is to be understood that the invention is also applicable to grease cups, grease lines, and the like for the supplying, dispensing or charging of grease thereto.

While we have herein described and upon the drawings shown an illustrative embodiment of the invention, it is to be understood that the invention is not limited thereto but comprehends other constructions, arrangements of parts, details, features and the like without departing from the spirit of the invention.

Having thus disclosed the invention, we claim:

1. A grease gun charger comprising a pair of telescopically and mutually reciprocable hollow cylinders having valves at their outer ends for controlling the movement of grease in one direction through said cylinders when said cylinders are mutually reciprocated, the inner end of the inner cylinder of said cylinders having an opening for the full extent of the cross-sectional area of said inner cylinder, a diaphragmatic type of piston attached to the outer end of one of said cylinders and being of a size to sealingly and slideably fit into a commercial type of grease container for forcing grease from said container into said cylinders under the force of atmospheric pressure acting on said piston in said container, and said piston having a port opposite the valve in the outer end of the cylinder to which said piston is attached.

2. A grease gun charger comprising a pair of telescopically and mutually reciprocable hollow cylinders having valves at their outer ends for controlling the movement of grease in one direction through said cylinders when said cylinders

are mutually reciprocated, the inner end of the inner cylinder of said cylinders having an opening for the full extent of the cross-sectional area of said inner cylinder, a diaphragmatic type of piston attached to the outer end of one of said cylinders and being of a size to sealingly and slideably fit into a commercial type of grease container for forcing grease from said container into said cylinders under the force of atmospheric pressure acting on said piston in said container, and said piston having a port opposite the valve in the outer end of the cylinder to which said piston is attached, and said port having a valve seat for the seating thereon of said last mentioned valve.

3. A grease gun charger comprising a pair of telescopically and mutually reciprocable hollow cylinders having valves at their outer ends for controlling the movement of grease in one direction through said cylinders when said cylinders are mutually reciprocated, the inner end of the inner cylinder of said cylinders having an opening for the full extent of the cross-sectional area of said inner cylinder, a diaphragmatic type of piston attached to the outer end of one of said cylinders and being of a size to sealingly and slideably fit into a commercial type of grease container for forcing grease from said container into said cylinders under the force of atmospheric pressure acting on said piston in said container, and said piston having a port opposite the valve in the outer end of the cylinder to which said piston is attached, and said piston having a rim provided with packing means for sealingly engaging with the wall of said container.
